US0D1004654S

(12) **United States Design Patent** (10) **Patent No.:** **US D1,004,654 S**
(45) **Date of Patent:** **** Nov. 14, 2023**

(54) **FRICITION STIR WELDING TOOL**

(71) Applicant: **Element Six (UK) Ltd**, Didcot (GB)

(72) Inventor: **Brian Gilroy**, Didcot (GB)

(73) Assignee: **Element Six (UK) Limited**,
Oxfordshire (GB)

(**) Term: **15 Years**

(21) Appl. No.: **35/515,714**

(22) Filed: **Jun. 1, 2022**

(80) **Hague Agreement Data**

Int. Filing Date: **Jun. 1, 2022**

Int. Reg. No.: **DM/224153**

Int. Reg. Date: **Jun. 1, 2022**

Int. Reg. Pub. Date: **Dec. 2, 2022**

(30) **Foreign Application Priority Data**

(57)

CLAIM

The ornamental design for a friction stir welding tool, as
shown and described.

DESCRIPTION

1. Friction stir welding tool

1.1 : Back

1.2 : Front

1.3 : Left

1.4 : Bottom

1.5 : Perspective

1.6 : Right

1.7 : Top

This design relates to a friction stir welding tool.

1 Claim, 7 Drawing Sheets
